N° 998

James L. Jackson

Design for a Screen for Steam Pipes &c.

Patented April 13, 1884.

Des. 998

James L. Jackson of New York N.Y.
Letters Patent No. 998 Dated April 13, 1838.

The schedule referred to in these Letters Patent & making part of the same.

To all whom it may concern:-

Be it Known that I, James L. Jackson, of the city, County and State of New York have invented or produced a new and original design for a screen for steam pipes, or other similar purpose, and do hereby declare the following to be a full, clear and exact description of the same reference being had to the accompanying drawings making a part of this specification.

My design consists in the ornamental parts of the plates, as will be hereafter explained - and its object is to make an open work screen for steam pipes or other similar purposes.

The front plate has a large central panel A, and on each side of it, smaller panels B.B. The centerpiece of the panel A, is a birdsnest, a, with

Des. 998

young birds in it, in the act of being fed by one of the parent birds, b, whilst the other or mate, c, is watching. Over the birds and nest hangs a bunch of grapes d, with grape leaves and tendrils. A beading of scroll work, e, surrounds the center piece, and between is volute tracery with foliage, the whole of the ground being open work. These volute stems and foliage start from a foliated urn, f, underneath the center piece. The corners underneath the beading, e, are filled in with stems and foliage, g, of water plants. And the upper corners with foliated volute tracery, h. The ground of the entire plate is open.

On each side of this central panel A, there is a side panel, having for its center a pendant of fruit, i, j, k, enclosed in an oval beading, l, the space between the beading and pyramid, being filled in with open work, m. Out side of the oval, l, there is another delicate oval bead, n, pendant from a volute, o - and outside of this again there are vertical beads, p, between which and the oval, l, there is volute stems and foliage as shown in the drawing. The narrow panels, q, are filled in with volutes and drops, r; and the other narrow panels, s, with the exception of their center piece t, is filled up with lattice work, u. The top and bottom of the plate, is margined by an ogre ornament, v, and beyond this with moldings, w. The end pilates, have the same ornament, as the side panels B. The top may be a plain plate or slab.

Having thus fully described my design, what I claim is the ornamental plates herein shown and represented, by the drawings, for a screen for steam pipes or other similar purposes.
